GUSTAVE HOLTER, OF SEATTLE, WASHINGTON.

HYDRAULIC MOTOR.

1,160,510.

Specification of Letters Patent.

Patented Nov. 16, 1915.

Application filed July 6, 1914. Serial No. 849,051.

To all whom it may concern:

Be it known that I, GUSTAVE HOLTER, a subject of the King of Norway, residing at Seattle, in the county of King and State of Washington, have invented a certain new and useful Improvement in Hydraulic Motors, of which the following is a specification.

My invention relates to improvements in hydraulic motors and more particularly it relates to that class of hydraulic motors which embody hollow cylinders wherein are disposed pistons that are adapted by suitable mechanism to be moved reciprocally by the force of flowing water to actuate an associated centrally fulcrumed lever to cause such lever to oscillate to communicate power to different mechanical devices with which such lever may be connected, and the object 20 of my improvement is to provide a hydraulic motor which shall be simple in its play of construction, durable and efficient in its operation and which shall be adapted when submerged in a fixed position within the 25 swift current of a river or stream of water so that its actuating parts may be subjected to the impact of such current; or when such actuating parts are subjected to the action of water supplied by pipes from a 30 higher elevation. I accomplish this object by devices illustrated in the accompanying drawings wherein—

Figure 1 is a plan view of one form of a hydraulic motor embodying my invention, 35 some parts of which are shown in their horizontal mid-section; Fig. 2 is a view in end elevation of the same; Fig. 3 illustrates another form of my invention by a plan view wherein some parts are shown in their 40 horizontal mid-section and Fig. 4 is an end view in elevation of the same.

Referring to the drawings, throughout which like numerals indicate like parts, 6 is a bed-plate arranged to rest horizontally 45 upon the bottom of a flowing stream upon which is mounted two hollow open ended cylinders 7 and 8 which are secured by bolts 9 that extend through flanges 10 and 11, which are integral with the walls of said 50 cylinders 7 and 8 respectively. Within each of said cylinders 7 and 8 is disposed a closely fitting piston, as pistons 12 and 13, of cup-like form, which pistons 12 and 13, are adapted to reciprocate within the cylinders 7 55 and 8 and which are respectively secured to piston rods 14 and 15 that extend through

guides 16 and 17 that are associated with the upper portion of the frame 6.

The lower ends of the pistons 12 and 13 are provided with semicircular stops or shoulders 18 against which the top surface of approximately one half of the circumference of disk shaped and pivotally mounted valves 19 and 20 are adapted to engage when such valves are closed and such pistons 65 are further provided with other oppositely disposed semicircularly shaped stops 21 against which the bottom surfaces of the opposite halves of the valves 19 and 20 are adapted to rest when such valves are closed, 70 which valves, when they are closed, form a solid bottom in the pistons 12 and 13, and when they are open they permit liquid freely to pass through such pistons.

The piston rods 14 and 15 at a point approximately midway between their two ends are provided with fixed collars 22 and 23 with which the two ends of a walking beam 24 are articulated by links 25 and 26, the walking beam 24 being fulcrumed on the 80 frame 6 by a centrally disposed pivot 27 and having two other piston rods 28 and 29 articulated therewith by links 30 and 31 which are secured to the beam 24 at points between the pivot 27 and each end of the 85 beam 24 respectively, the piston rods 28 and 29 projecting upwardly into two pump cylinders 32 and 33, respectively whereby, when the beam 24 is oscillated about the pivot 27, pistons (not shown) that are provided on 90 the ends of the piston rods 28 and 29, will be reciprocated within the cylinders 32 and 33 to lift a relatively small amount of water to a high elevation, such water being drawn inwardly through the pipes 34 and 95 forced outwardly through the pipes 35.

The piston valves 19 and 20 are pivotally secured within the pistons 12 and 13, respectively, by pivot shafts 36 and such valves are provided with upwardly projecting bifurcated brackets or lugs 37 and 38, respectively, with which are articulated the lower ends of opening and closing links 39 and 40 which project upwardly and out of the cylinders 10 and 11 and which are articulated 105 with the two ends of a cross-beam 41 that is fulcrumed at its medial point on a pivot 42 that passes through a portion of the frame 6 whereby the beam 41 may oscillate with the beam 24.

Articulated with the beam 24, at points between the pivot 27 and the two ends respec-

tively, of such beam 24, are two downwardly projecting links 43 and 44 that have their lower ends pivotally secured to the inner ends of lever arms 45 and 46, which lever arms are fulcrumed on pivots 47 and 48 provided on the frame 6, and which are each disposed to have an outer end extend outwardly past the opening and closing links 39 and 40 in close proximity to such links whereby the ends of such lever arms 45 and 46 may engage with pins 49, 50, 51, and 52 at certain predetermined periods, during the movement of the links 39 and 40, to open and close the valves 19 and 20.

In Fig. 3, wherein I have illustrated a modified form of my invention, 53 and 54 are pistons similar to the pistons 12 and 13 except that each of such pistons is provided near its bottom end with three valve stops 55, 56 and 57, respectively, there being pivotally mounted in the lower end of the piston 53 two semicircular valve disks 58 and 59, and in the piston 54 two similarly formed semicircular valve disks 60, 61, such valve disks being provided with bifurcated lugs 62, 63, 64 and 65, respectively, with which are pivotally connected the lowermost ends of links 66, 67, 68 and 69, the links 67 and 68 being identical with the links 39 and 40 and being provided with similar engaging lugs 75, 76, 77 and 78, and the links 66 and 69 being pivotally secured to the links 67 and 68 by the same pivots 70 and 71 by which such links 67 and 68 are secured to the end of a fulcrumed cross-bar 72 that is similar to the cross-bar 41, other parts of the device shown in Fig. 3 being identical with similar parts shown in Fig. 1 wherein they are indicated by similar reference numerals.

The operation of my device, as illustrated in Fig. 1 may be described as follows: The bottom ends of the cylinders 7 and 8 may be connected with pipes 73 and 74 through which water under pressure is caused to flow in the direction, shown by the arrows, and if the device be in the position shown, such flowing water will exert force against the valve 19 and will move against the piston 12 upwardly within the cylinder 7, the piston 13 at the same time moving downwardly in the cylinder 8 with its valve 20 open, as shown in Fig. 1. As the piston 12 moves upwardly it lifts the end of the beam 24 and also lifts the opening and closing link 39 together with the end of the beam 41. The link 43 moves upwardly with the end of the beam 24 and the outer end of the lever arm 45 moves downwardly as the arm 24 is raised, until the outer end of such lever arm 45 engages with the pin 50 in the link 39 and causes such link to open the valve 19 while at the same time the lever arm 46, which has been moving in a direction opposite to the direction of movement of the link 45, engages with the pin 51 to close the valve 20,

the valve 19 opening at the end of its working stroke at the same instant that the valve 20 closes at the end of its idle stroke and the water that is flowing through the pipe 74 and the cylinder 8 engaging with the valve 20 to move the piston 13 upwardly thus reversing the direction of movement of the various links and levers connected therewith. The pistons 12 and 13 thus continue their reciprocal motions within the cylinders 7 and 8, the valves 19 and 20 each closing at the bottom of its stroke and opening at the top of its stroke, and the movement of the piston rods 14 and 15 impart a rocking or oscillating motion to the beam 24 and a consequent reciprocatory movement to the piston rods 28 and 29 which reciprocatory movement may be utilized by mechanism, not herein shown in detail, to pump water into and out of the cylinders 32 and 33. The pins in the opening and closing links 39 and 40, in their movement in one direction encounter the ends of the levers 45 and 46 which are then moving in an opposite direction thus causing the valves 19 and 20 to be quickly and surely shifted from an open to a closed or from a closed to an open position, as the case may be, such shifting of the valves being much more quickly accomplished by reason of the movement of the lower arms 45 and 46 than it could be accomplished if the pins 49, 50, 51 and 52 were caused to engage with fixed devices on the frame as might be done.

The operation of the device shown in Figs. 3 and 4, is similar to the operation of the device shown in Figs. 1 and 2, except that each of the pistons 53 and 54 is provided with a two part valve instead of a single valve, such two part valves being pivotally mounted within the pistons 53 and 54 and there adapted, when closed, to rest against the valve stops 55, 56, and 57, and each part of each of such valves is connected with a suitable link by which such valve part may be moved from an open to a closed or from a closed to an open position. Fig. 4 shows the valve sections 58 and 59 closed in such manner that water impinging against such valve sections will move the piston 53 upwardly until the end of the link 45 strikes against the pin to open such valve sections 58 and 59 at the end of the working stroke of the piston 53, the end of the link 46 striking against the pin 78 at the same instant and closing the valve sections 60 and 61 to reverse the direction of movement of the various parts.

My hydraulic motor is adapted to operate when submerged in a swiftly flowing current of water or it may be connected with pipes through which water under pressure is flowing and may be operated by the pressure of the water in such pipes.

Obviously, numerous changes in the form

of the various details embodied in my hydraulic motor may be resorted to without departing from the spirit of my invention or sacrificing any of its advantages.

5 What I claim is:

1. In a hydraulic motor of the class described, the combination with a frame, of two cylinders secured to said frame, a piston disposed to be movable in each of said 10 cylinders, piston rods connected with said pistons, a walking beam pivotally secured to said frame, said walking beam being pivotally connected at each end with one of said piston rods, valves pivotally disposed in each of said pistons, opening and closing links articulated with each of said valves and provided with limit stops, lever arms pivotally secured to said frame, and links connecting said lever arms with said walking beam whereby said lever arms may be caused to engage the limit stops of opening and closing links to open or close said 20 valves.
2. In a hydraulic motor of the class described, the combination with a frame, of two cylinders secured to said frame, pistons disposed in said cylinders, piston rods secured to said pistons, a walking beam having its ends articulated with said piston rods and its medial point pivotally secured to said frame, lever arms fulcrumed on said frame, links connecting said lever arms with said walking beam, valves pivotally mounted in said piston, links connected with said valves and adapted to be actuated by said lever 35 arms to open said valves when said pistons are at the end of their working stroke and to close said valves when said pistons are at the end of their idle stroke.

In witness whereof, I hereunto subscribe 40 my name this 26th day of June A. D., 1914.

GUSTAVE HOLTER.
